CUSHIONING DEVICE FOR SHOULDER STRAPS

Claud F. Crawford, Pasadena, Calif., assignor to The Scholl Mfg. Co., Inc., Chicago, Ill., a corporation of New York

Application March 25, 1955, Serial No. 496,752

1 Claim. (Cl. 2-2)

This invention relates to improvements in a cushioning device for shoulder straps, and more particularly to a soft cushioning element for disposition beneath the shoulder straps of a user to eliminate objectionable and uncomfortable frictional contact of those shoulder straps with the shoulders of a user, although the invention may have other uses and purposes as will be apparent to one skilled in the art.

In the past, many and various types of devices have been developed for preventing shoulder straps of slips, brassieres, and other female undergarments from grooving, chafing, or otherwise irritating the shoulders of a user, but these formerly known devices have been objectionable in that they were not as comfortable as might be desired, were prone to migrate from their desired location in some instances, were not as easily and readily attachable and removable as may be desired, could not be laundered in many cases whenever desired, and in other instances were uncomfortably warm in the region of contact with the body. Furthermore, shoulder cushioning devices of this character were frequently objectionably expensive as heretofore made. In addition, devices of this character heretofore known frequently caused unwelcome bulges detracting from the appearance of outer garments.

With the foregoing in mind, it is an important object of the instant invention to provide a soft and comfortable cushioning device for shoulder straps which may quickly and easily be connected with and disconnected from one or more shoulder straps.

Also an object of the invention is the provision of a cushioning device for shoulder straps affording an even and uninterrupted contact with the shoulder of a user, with extremely simple means for connecting the cushioning device with one or more shoulder straps.

It is also an object of this invention to provide a cushioning device for shoulder straps in the form of a soft pad-like member of such character as to provide a gentle clinging contact with the skin of the user, and simple means for connecting one or more shoulder straps with the pad over the upper surface of the pad.

It is also a feature of this invention to provide a simple form of cushioning device for shoulder straps embodying a laminated pad, comprising a relatively thick lower layer of cushioning material, and a relatively thin cover member, the cover member only being provided with one or more pairs of laterally spaced slits, there being a ribbon passing through each pair of slits, with simple means for removably connecting the ends of the ribbon.

Still a further object of the invention resides in the provision of a cushioning device for shoulder straps embodying a relatively thick layer of foam latex for contact with the body of the user, and a thin skin-like rubber covering over the foam latex, the cover being provided with one or more pairs of laterally spaced slits therein, and the cover being secured to the foam latex cushioning element elsewhere than between a pair of slits, being free from the foam latex cushioning member in that region

2

to accommodate a simple ribbon threaded through the slits and provided with complementary snap fastening means to removably connect the free ends of the ribbon over one or more shoulder straps.

5 While some of the more salient features, characteristics and advantages of the instant invention have been above pointed out, others will become apparent from the following disclosures, taken in conjunction with the accompanying drawing, in which—

10 Figure 1 is a fragmentary diagrammatic illustration of the upper part of the female body showing a pair of cushioning devices embodying principles of the instant invention in operative position;

15 Figure 2 is an enlarged top plan view of one of the cushioning devices illustrating one securing means in closed position, and the other in open position;

Figure 3 is an enlarged transverse vertical sectional view taken substantially as indicated by the line III—III of Fig. 2, looking in the direction of the arrows; and

20 Figure 4 is an enlarged longitudinal vertical sectional view taken substantially as indicated by the line IV—IV of Fig. 2.

As shown on the drawings:

25 In Fig. 1 of the drawings there is shown the upper portion of a female torso designated by numeral 1, provided with a garment 2 in the form of a brassiere having a pair of shoulder straps 3—3. These shoulder straps pass over and are connected with cushioning devices, generally indicated by numerals 4—4, embodying principles of the instant invention.

30 Now with reference to Figs. 2, 3 and 4, it will be seen that each of the cushioning devices embodies a laminated pad comprising a relatively thick layer 5 of cushioning material. This layer 5 is preferably made of foam latex 35 of the character having intercommunicative cells so as to be somewhat ventilative in character. Foam latex of this character is extremely light in weight, soft and gentle yet clinging in contact with the human skin, and the lower surface of the layer 5 is preferably uncovered so that the 40 foam latex is directly in contact with the skin of the user. Over the layer 5 is a relatively thin skin-like cover 6 which is preferably of a thin rubber of the general character of dental dam rubber. This material is stronger in character than the foam latex, not prone to tear, and 45 presents a relatively smooth outer surface over which a shoulder strap may readily slide in response to bodily movements of the user.

45 The composite laminated pad is preferably provided with a serrated bounding edge 7 therearound, the serrations increasing the length of the bounding edge and providing a better and closer fit of a tight outer garment by virtue of the gradual and increasing depression of the teeth of the serrations toward the points thereof.

50 The top skin-like cover layer of the laminated pad is provided with one or more pairs of laterally spaced slits as indicated at 8, two such pairs being shown in the illustrated example. The upper layer is bonded to the lower foam latex layer, preferably by vulcanizing or in an equivalent manner, elsewhere than between each pair 55 of slits, and the upper layer is free from any bond with the lower layer between the slits of each pair.

55 Threaded through the slits of each pair, as clearly seen in Figs. 3 and 4, is a ribbon or strap 9, which may 60 well be made of a suitable silken fabric of any desirable color. Thus, the engaged portion of each ribbon or strap underlies the cover lamination 6, but overlies the lower cushioning lamination 5. One end of each strap or ribbon is provided with a suitable male snap member 10, and the opposite end is provided with a complementary 65 female snap member 11 which are of the type of well known snap fasteners.

70 It is a simple expedient to open the snap fastening ele-

ments of a ribbon, thread the end sufficiently to place the shoulder strap or straps therebetween, and then re-engage the snap fastening elements so as to removably attach the shoulder strap or straps to the cushioning device, and with the shoulder straps overlying the cushioning device lengthwise. The cushioning devices may be left engaged with the shoulder straps if so desired, or easily opened and removed when the undergarments are removed.

It will be noted that each cushioning device provides a soft gentle clinging contact with the shoulder of the user, effectively prevents any rubbing, chafing, or objectionable pressure contact with the shoulder of the user by the shoulder straps of undergarments, and each cushioning device will accommodate one or a plurality of shoulder straps. The cushioning devices are economical in construction, extremely simple to operate, highly durable, may be readily laundered in their entirety whenever desired, and are extremely economical to manufacture and use.

It will be understood that modifications and variations may be effected without departing from the scope of the novel concepts of the present invention.

I claim as my invention:

In a cushioning device for shoulder straps, a flat laminated pad including a relatively thick layer of foam cushioning material, and a thin skin-like layer of rubber-like material over said foam layer, said skin-like layer only having a pair of transversely spaced longitudinally extending slits therein and being secured to said foam layer elsewhere than between said slits to define a transversely extending elongated loop integral with the skin-like layer, a ribbon threaded through said loop, and snap-fastener means carried by the ends of said ribbon to unite said ends over a shoulder strap.
